RADIO CABINET

Duane Swibold, Interlochen, Mich.

Application July 26, 1947, Serial No. 140,548

Term of patent 14 years

(Cl. D56—4)

To all whom it may concern:

Be it known that I, Duane Swibold, a citizen of the United States of America, and residing at Interlochen, county of Grand Traverse, State of Michigan, have invented a new, original, and ornamental Design for a Radio Cabinet, of which the following is a specification, reference being had to the accompanying drawings, forming part thereof.

Figure 1 is a perspective view of a radio cabinet, showing my new design.

Figure 2 is a side elevation thereof.

Figure 3 is a perspective view of the base portion of the radio cabinet.

The other side of the cabinet, not shown, is substantially the same as the side shown.

The characteristic features of my design reside in the portions shown by means of full lines in the drawing.

I claim:

The ornamental design for a radio cabinet, substantially as shown and described.

DUANE SWIBOLD.
